Patented Oct. 14, 1924.

Des. 65,777

UNITED STATES PATENT OFFICE.

FRANK L. HALE, OF BROOKLYN, NEW YORK.

DESIGN FOR AN ASH TRAY.

Application filed June 4, 1920. Serial No. 386,599. Term of patent 3½ years.

To all whom it may concern:

Be it known that I, FRANK L. HALE, a citizen of the United States of America, residing at 55 Hanson Place, Brooklyn, in the county of Kings and State of New York, have invented certain new, original, and ornamental Design for Ash Trays, of which the following is a specification.

Reference is had to the accompanying drawings forming a part hereof.

The figure is a perspective view of the ash tray.

I claim:

The ornamental design for an ash tray, as shown.

In testimony whereof I have affixed my signature.

FRANK L. HALE.
